UNITED STATES PATENT OFFICE.

CHARLES H. TONNDORFF, OF ST. LOUIS, MISSOURI, ASSIGNOR, BY DIRECT AND MESNE ASSIGNMENTS, TO HENRY KUHN AND THE M. A. SEED DRY PLATE COMPANY, BOTH OF SAME PLACE

PHOTOGRAPHIC NEGATIVE-PLATE

SPECIFICATION forming part of Letters Patent No. 375,231, dated December 20, 1887.

Application filed March 29, 1886. Serial No. 197,012. (No model.)

To all whom it may concern:

Be it known that I, CHARLES H. TONNDORFF, of St. Louis, Missouri, have made a new and useful Improvement in Photographic Negative-Plates, of which the following is a full, clear, and exact description.

The present invention is a new article of manufacture supplied to the trade and to others, and by them used as other photographic negative-plates are used, saving as such use is modified by the improved feature of the plate, which consists in an undeveloped impression that, by means of a preliminary exposure, is produced in that part of the sensitive film of the plate which surrounds or is at the side of that part of the film where the picture is to be produced.

The improvement is especially valuable in that it enables photographic negative-plates to be furnished to the trade and to users with an undeveloped vignette or border already in the plate-film, which vignette or border can, along with the picture produced by means of a second exposure within or at the side of the vignette or border, be ultimately developed upon the plate, and thereby obviate the need of employing a vignette apparatus at the time of printing the positive.

In carrying out the improvement I take what is known to the trade as a "dry-plate" and expose it to the light under or in the rear of a cliché or mask whose shape is complementary to that of the desired vignette or other impression—that is, to produce a vignette, a

cliché, suitably constructed at its periphery 35 to produce a vignette and of proper size and shape to cover the central portion of the film where the picture ultimately is to be taken is placed over or in front of the central portion of the dry-plate, and then the masked 40 plate is exposed to the light, in doing which care should be taken to let the light strike the plate at right angles in front. An exposure of a second or two is sufficient.

A cliché produced by photographic methods I consider the most desirable one to use, although other kinds—such, for instance, as stained glass—can be used with good results. To produce a border, or something having a sharp outline, a cliché having a corresponding sharp outline is employed. The dry-plates having the impression thus produced in the film are of course kept from the light until the time of the second exposure for taking the picture, when it is exposed in the ordinary 55 manner in the camera.

I claim—

As a new article of manufacture, a photographic negative-plate having an undeveloped vignette or border upon that part of the plate-film which surrounds or partially surrounds the space to be occupied by the desired picture.

CHARLES H. TONNDORFF.
